(57) **CLAIM**

The ornamental design for a key, as shown.

DESCRIPTION

The claimed decorative key is intended to open the lock on a casket or the like. The key may also be worn as a pendant on a necklace or a bracelet.

FIG. 1 is a front elevational view of a key showing our new design;

FIG. 2 is a left side elevational view thereof;

FIG. 3 is a right side elevational view thereof;

FIG. 4 is a top plan view thereof;

FIG. 5 is a bottom plan view thereof; and,

FIG. 6 is a rear elevational view thereof.

1 Claim, 1 Drawing Sheet
